THROTTLE CONTROL MECHANISM

Lee C. Daniels, Cleveland, Ohio, assignor to The
White Motor Company, Cleveland, Ohio, a cor-
poration of Ohio

Application April 27, 1935, Serial No. 18,652

4 Claims. (Cl. 261—23)

This invention relates to internal combustion engines, and more particularly to throttle control mechanisms of the type described in my earlier application, Serial No. 17,567, filed April 22, 1935.

As explained in my earlier application, it is often desirable in the construction of motor vehicles embodying a plurality of engines, and in the construction of motor vehicles embodying a single engine constructed with a plurality of fuel induction systems, to connect the throttles of the separate fuel induction systems for simultaneous operation, but due to inaccuracies in construction of the carburetors producing differences in the ranges of throttle movement between idle positions and the positions at which the main carburetor jets come into action difficulty has been encountered in connecting the throttles in the manner specified.

It is an object of this invention to provide an improved throttle control mechanism of the type above set forth which can be readily adjusted to compensate for inaccuracies in the construction of the carburetors.

It is a further object of this invention to provide an improved throttle mechanism for use with a plurality of carburetors which can be readily adjusted to compensate for inaccuracies in the construction outside the carburetors.

Other objects will appear in the following description of one practical embodiment of the invention illustrated in the accompanying drawing, in which:

Figure 1 is a perspective view of an engine constructed with two sets of opposed cylinders and with separate fuel intake systems for the two banks of cylinders, together with a control mechanism for the throttle valves of the intake systems.

Figure 2 is a diagrammatic view illustrating the various positions of the parts of the throttle control mechanism with the throttles in idling positions.

Figure 3 is a diagrammatic view illustrating the positions of the various parts of the throttle control mechanism with the throttles in partially opened positions.

Figure 4 is a sectional view of one of the carburetors shown in Figure 1.

Figure 5 is an elevational view of the lower portion of the carburetor illustrated in Figure 4, showing the mechanism carried by the operating shaft of the throttle valve, and

Figure 6 is a similar view to Figure 5 taken

at a right angle thereto and showing only a part of the lower portion of the carburetor.

The engine illustrated in the drawing comprises two banks of cylinders 10 and 11 of like construction which are fed by two fuel induction systems A and B of like construction. The fuel induction systems A and B each comprise an inlet manifold 12, a short inlet pipe 12a, and a carburetor 13.

The carburetors 13 although oppositely disposed are exactly alike in construction, and a description of the one shown at the right in Figure 1 and illustrated in section in Figure 4 will serve the purpose of this disclosure. Such carburetor comprises a float chamber 14 and a tubular intake portion 15 which communicates with the intake manifold 12 through the pipe 12a. The float chamber 14 is provided with a fuel inlet 16, and with a float 17 and a needle valve 18 which cooperate to automatically control the level of the fuel in the float chamber. A vent for the float chamber is provided in the form of a duct 19 which forms a communicating passage between the upper part of such chamber and a passageway 20 leading to the outside atmosphere.

The upper end of the tubular portion 15 serves as an air intake and is controlled by a conventional choke valve 21. Located in the central part of the tubular portion 15, there is a venturi 22 which communicates at its lower end with a mixing chamber 23 at the lower end of the tubular portion. Mounted within the mixing chamber 23, there is a rotatably mounted throttle valve 24 of the butterfly type, the shaft 24a of which extends through the wall of the tubular portion 15 for connection to the throttle operating mechanism.

Projecting into the venturi 22 from the wall of the tubular portion 15, there is a nozzle 25 the outlet end of which extends into the throat of the venturi 22. This nozzle constitutes the main jet of the carburetor, and is arranged and fed in such a manner that no fuel is drawn therefrom during idling of the engine. Such nozzle is fed directly from the float chamber through a duct 26, a well 27, and a tubular member 28 formed with a calibrated orifice 28a at its lower end. Such nozzle is further fed by way of two ducts 29 and 30 from a gravity well 31 which communicates with atmosphere through a duct 32 and the passageway 20 and receives its supply of fuel from the float chamber through a duct 33 and a member 34 formed with a calibrated orifice 34a.

In addition to the nozzle 25, the carburetor is constructed with means for supplying fuel to the engine during idling of the engine. Such means comprises a well 35 composed of a duct 35a formed in the wall of the tubular portion 15 and a tube 35b mounted in a bore 36 in the wall of the tubular portion. The well 35 is supplied with fuel from the gravity well 31 by way of the ducts 29 and 30, a passage 31 existing between the tube 28 and the wall of the nozzle 25, a duct 38 leading around the periphery of the tubular portion 15, a passage 39 formed by cutting a notch in the circumference of the tube 35b, a second passageway 40 formed by cutting a longitudinally extending slot in the tube 35b, and an aperture 41 formed in the upper end of the tube 35b.

The upper end of the well 35 communicates through a duct 42 with a duct 43 leading into the interior of the tubular portion, and an adjustable needle valve 44 equipped with a retention spring 44a is provided to adjust the flow of air thereto from the interior of the tubular portion. At its lower end, the well 35 communicates with the interior of the mixing chamber through a discharge orifice 45 constituting the idling jet.

When the engine is idling, fuel is supplied to the mixing chamber by the fuel system last described, the suction within the venturi 22 at such time being insufficient to draw fuel from the nozzle 25. As the throttle valve 24 is opened, a point is reached at which the suction created in the venturi is sufficient to draw fuel from the nozzle 25. At this time, the fuel supplied to the well 35 of the idling system is cut off due to all fuel from the well 31 being drawn into the nozzle 25, and from that time on fuel is supplied solely by the nozzle 25.

Fixed upon the shaft 24a of the throttle valve of each of the carburetors, there is a member 46 formed with two depending arms 46a and 46b and with a vertically extending arm 46c. The arms 46a of the members 46 carry screws 47 equipped with retention springs 47a and are designed for engagement with members 48 protruding from the sides of the carburetors to limit closing movement of the throttle valves. The arms 46b of the members 46 are designed for engagement with the members 48 to limit opening movement of the throttle valves, and the arms 46c to serve as throttle actuating levers in the manner hereafter described.

Rotatably mounted upon the shaft 24a of the throttle valve of each of the carburetors, there is a lever 49 formed at its upper end with an arm 49a located at the side of the arm 46c in which such arm moves in closing the throttle valve, and with an arm 49b located on the opposite side of the arm 46c. Mounted in the arm 49a of each of the levers 49, there is an adjustable screw 50 designed to engage with the arm 46c and equipped with a lock nut 50a; and supported in recesses formed in the arms 49b and 46c of the mechanisms associated with each carburetor, there is a compression spring 51 which urges the arm 46c against the screw 50.

The rotatably mounted levers 49 are held in place by plates 52 secured to the arms 46c of the members 46 by means of screws 53, and are connected with a pivotally mounted foot pedal 54 through a linkage mechanism C. The linkage mechanism C comprises a cross shaft 55 rotatably mounted on the front of the engine and equipped with two oppositely disposed levers

56 and 57 at its ends and an intermediately mounted lever 58. The levers 56 and 57 are connected to the lower ends of the levers 49 by means of pull rods 59 and 60, and the lever 58 to the lower end of the foot pedal 54 by means of a pull rod 61. The pedal 54 is maintained in an elevated position by a tension spring 62 connecting the forward end of the pull rod 61 with a bracket 63 secured to the flooring which supports the pedal 54. As will readily be seen, the organization of the linkage is such that depression of the foot pedal 54 causes forward movement of the pull rod 59 and rearward movement of the pull rod 60, and the release of the foot pedal 54 reverse movements of the pull rods 59 and 60.

The throttle control mechanism described in the foregoing provides for an adjustment whereby inaccuracies in carburetor construction resulting in different ranges of throttle movement between idling positions and the positions at which the main carburetor jets come into action can be compensated for. When not compensated for, such inaccuracies cause the throttle valve of one carburetor to reach a position at which the main jet comes into action in advance of the throttle valve of the other carburetor, and to thereafter maintain a lead over the valve of the other carburetor throughout the range of throttle control for working conditions of the engine. This inconsistency in the operation of the two throttle valves causes the two banks of cylinders of the engine to be fed differently, and produces what is known as rough operation of the engine.

Under a preferred method of adjusting the throttle mechanism, the spring 62 is first replaced by a substitute spring incapable of compressing the springs 51 and the screws 50 adjusted so that the arms 46c occupy positions substantially midway between the arms 49a and 49b. The engine is then started and the screws 47 and 50 adjusted in such a manner that the engine idles properly under no load with the screws 47 in engagement with the members 48, after which the substitute spring is removed and the original spring 62 installed compressing the springs 51. Following the replacement of the substitute spring by the original spring 62, the speed of the engine is increased by depressing the foot pedal 54 until the main jet of one of the carburetors is brought into action. The point at which this occurs is observed from the top of the carburetor by noting the position at which the face of the throttle valve becomes wet. The screw 50 of the other carburetor is then adjusted in such a manner that the throttle valve occupies a position in its movement at which the main jet of the carburetor has just been brought into action, such operation completing the adjustment of the throttle operating mechanism.

Upon release of the foot pedal 54 following adjustment of the throttle mechanism as described, the throttle valves are moved towards their idling positions by the spring 62 acting through the linkage C. In the absence of a very rare condition when certain inaccuracies in construction compensate for other inaccuracies, one of the throttle valves will reach its idling position before the other throttle valve, with the result that further actuation of the linkage C by the spring 62 will act to move the arm 46c associated with the throttle valve first reaching its idling position away from the

arm 49a compressing the associated spring 51. As the linkage C is further actuated by the spring 62 the arm 46c of the other carburetor is moved away from the screw 50 compressing the associated spring 51. The movement of the parts of the throttle mechanism by the spring 62 is terminated by the arm 46c associated with the throttle valve first reaching its idling position being brought into engagement with the associated arm 49b. Should the inaccuracies in construction compensate one another, the throttle valves will simultaneously reach their idling positions, followed by the arms 46c being simultaneously moved away from the screws 50 and brought into engagement with the arms 49b to terminate actuation of the throttle mechanism by the spring 62.

Figure 2 illustrates diagrammatically the relation of parts, with the foot pedal released in a control mechanism which has been adjusted in accordance with the preceding method, and in which the inaccuracies of construction do not compensate one another, and Figure 3 the relation of parts with the foot pedal partially depressed.

In cases in which the inaccuracies in construction compensate one another, the throttle valves will move together during all phases of their movement in consequence of the screws 50 being so adjusted that they engage and disengage the arms 46c at the same time; and due to the throttle valves having been properly adjusted for idling of the engine and in such a manner as to simultaneously reach the positions at which the main jets of the carburetors come into action, smooth operation of the engine will result throughout the entire range of throttle control.

In cases in which the inaccuracies in construction do not compensate one another, the throttle valve which first reaches its idling position in retarding the throttle valves is first advanced toward an open position when the pedal 54 is depressed. Following a slight opening movement of such throttle valve, corresponding movement of the other throttle valve is initiated as a result of the screw 50 of the associated mechanism being moved into engagement with the arm 46c. Thereafter, the throttle valves move together simultaneously reaching the positions at which the main jets of the carburetors are brought into action. When the foot pedal is released, the throttle valves are returned to their idling positions, and the springs 51 compressed as described in the foregoing. As a result of the screws 47 having been properly adjusted the engine operates smoothly with the throttle valves in idling position, and due to the adjustment whereby the main jets 60 are brought into action at the same time the engine also operates smoothly under working conditions with the cylinders being supplied with fuel by way of the main jets.

Although the foregoing description is necessarily of a detailed character in order that the invention may be completely set forth, it is to be understood that the specific terminology is not intended to be restrictive or confining, and that various rearrangements of the parts and modifications in structural details may be resorted to without departing from the scope or spirit of the invention as claimed.

What I claim is:

1. The combination with a plurality of engine fuel supply systems each comprising a carbure-

tor constructed with a throttle valve, an idling jet, and a main jet which is rendered active by the creation of a predetermined pressure at its outlet, of members operatively connected to the throttle valves of the carburetors of said supply systems, means for limiting the closing movements of said throttle valves, a throttle control lever, linkage mechanism connecting said members with said throttle control levers including relatively movable parts associated with said members, adjustable means carried by said parts arranged for engagement with the opposite sides of said members from the direction in which said members move in opening said throttle valves, and springs connecting said members with said parts acting to urge said members against the aforesaid adjustable means, spring means capable of overcoming the aforesaid springs arranged to urge movement of said parts in a direction to close said throttle valves, and means for limiting movement of said parts in response to the action of said spring means, the arrangement being such that the said adjustable means can be adjusted in a manner to provide for complete closing movement of all of said throttle valves and in a manner to provide for simultaneous actuation of the main jets of said carburetors during opening of said throttle valves by said throttle control lever.

2. The combination with a plurality of engine fuel supply systems each comprising a carburetor constructed with a throttle valve of the butterfly type, an idling jet, and a main jet which is rendered active by the creation of a predetermined depression at its outlet, of operating levers fixed on the shafts of the throttle valves of the carburetors of said supply systems, means for limiting the closing movements of said throttle valves including adjustable means for varying the positions attained by said throttle valves at the ends of their closing movements, a throttle control lever, linkage mechanism connecting said operating levers with said throttle control lever including relatively movable levers associated with said operating levers, adjustable parts carried by said second mentioned levers arranged for engagement with the opposite sides of said operating levers from the direction in which said operating levers move in opening the throttle valves, and springs connecting said operating levers with said second mentioned levers arranged to urge said operating levers against the aforesaid adjustable parts, spring means capable of overcoming the aforesaid springs arranged to urge movement of said second mentioned levers in a direction to close said throttle valves, and means carried by said second mentioned levers for limiting movement of such levers in response to the action of said spring means, the arrangement being such that the aforesaid parts can be adjusted in a manner to provide for complete closing movement of all of said throttle valves and in a manner to provide for simultaneous actuation of the main jets of said carburetors during opening of said throttle valves by said throttle control lever.

3. The combination with a pair of engine fuel supply systems each comprising a carburetor constructed with a throttle valve of the butterfly type, an idling jet, and a main jet which is rendered active by the creation of a predetermined depression at its outlet, of operating levers fixed on the shafts of the throttle valves of the carburetors of said supply systems, means for limiting the closing movements of said throt-

tle valves including adjustable means for varying the positions attained by said throttle valves at the ends of their closing movements, a throttle control lever, linkage mechanism connecting 5 said operating levers with said throttle control lever including relatively movable levers associated with said operating levers, adjustable parts carried by said second mentioned levers arranged for engagement with the opposite sides 10 of said operating levers from the direction in which said operating levers move in opening the throttle valves, and springs connecting said operating levers with said second mentioned levers arranged to urge said operating levers 15 against the aforesaid adjustable parts, spring means capable of overcoming the aforesaid springs arranged to urge movement of said second mentioned levers in a direction to close said throttle valves, and means for limiting movement 20 of said second mentioned levers in response to the action of said spring means, the arrangement being such that the aforesaid parts can be adjusted in a manner to cause the main jets of the carburetors to be simultaneously brought 25 into action despite an initial opening of one of said throttle valves in advance of the other of said throttle valves.

4. The combination with a pair of engine fuel supply systems each comprising a carburetor constructed with a throttle valve of the butterfly type, an idling jet, and a main jet which is rendered active by the creation of a predeter-

mined depression at its outlet, of operating levers fixed on the shafts of the throttle valves of the carburetors of said supply systems, means for limiting the closing movements of said throttle valves including adjustable means for varying the positions attained by said throttle valves at the ends of their closing movements, a throttle control lever, linkage mechanism connecting said operating levers with said throttle control lever including levers rotatably mounted on the 10 shafts of the throttle valves of said carburetors and constructed with arms disposed on opposite sides of said operating levers from the direction in which said operating levers move in opening the throttle valve and with spaced arms located 15 on the opposite sides of said operating levers, adjustable screws mounted in said first mentioned arms arranged to engage with said operating levers, and compression springs mounted intermediate said second mentioned arms and 20 said operating levers acting to urge said operating levers against said screws, and spring means capable of overcoming the aforesaid springs arranged to urge movement of said second named levers in a direction to close said throttle valves, 25 the arrangement being such that the aforesaid screws can be adjusted in a manner to cause the main jets of said carburetors to be simultaneously brought into action despite an initial opening of one of said throttle valves in advance 30 of the other of said throttle valves.
